CLAIM

(57) The ornamental design for a fuel dispenser, substantially as shown and described.

DESCRIPTION

FIG. 1 is a perspective view from above illustrating the front and right side of a fuel dispenser;

FIG. 2 is a front view thereof;

FIG. 3 is a right side view thereof;

FIG. 4 is a rear view thereof;

FIG. 5 is a left side view thereof; and,

FIG. 6 is a top view thereof.

The bottom of the fuel dispenser of FIGS. 1-6 is flat and devoid of surface ornamentation and is not part of the claimed design.

The broken lines in FIGS. 1-6 around the fuel dispenser nozzle holder, the hose holder, and the payment terminal are directed to environment and are for illustrative purposes only and form no part of the claimed design. Additionally, the area inside the boundary of the broken lines forms no part of the claimed design.
